UNITED STATES PATENT OFFICE.

ARTHUR W. NELSON, OF CHICAGO, ILLINOIS, ASSIGNOR, BY MESNE ASSIGNMENTS, TO
AMERICAN ARCH COMPANY, OF NEW YORK, N. Y., A CORPORATION OF DELAWARE.

LOCOMOTIVE-FURNACE ARCH.

1,138,054.

Specification of Letters Patent.

Patented May 4, 1915.

Application filed September 24, 1913. Serial No. 791,642.

To all whom it may concern:

Be it known that I, ARTHUR W. NELSON, a citizen of the United States, and a resident of Chicago, county of Cook, and State of Illinois, have invented certain new and useful Improvements in Locomotive-Furnace Arches, of which the following is a specification.

My invention relates generally to improvements in boiler furnaces, and has particular reference to improvements in refractory arches for use with locomotive furnaces equipped with arch supporting tubes.

The general object of my invention is to improve and simplify the construction of such arches to the end that they can be cheaply built, easily and quickly installed, and maintained in efficient working condition with little labor and expense.

Another object of my invention is to provide a multiple brick arch for locomotive fire-boxes equipped with arch supporting tubes which shall require but a single form of brick for the entire arch; and a further

object is to provide an arch which at the same time shall be easily adjustable to considerable variations in the widths of the fire-boxes, to irregularities in the spacing or arrangement of the arch supporting tubes, to irregularities in the spacing of the side tubes from the side sheets, and to locomotives equipped with any number of arch tubes.

My invention consists generally in a locomotive fire-box having a group of arch tubes longitudinally arranged therein and spaced throughout the width thereof, in combination with a plurality of identical brick, each brick resting at one end directly upon a tube, and a number together closing the space between the side sheets.

My invention consists further in a locomotive fire-box having a group of longitudinally extending arch tubes spaced throughout the width thereof in combination with a refractory arch body arranged therein and closing the space between the side sheets, said arch body comprising a plurality of identical arch bricks, each brick resting upon a tube at one end and engaging the adjacent brick or side sheet with the other end.

My invention consists further in the unique arrangement, construction, and combination of parts whereby the objects named

above and others which will appear herein- 55 after are attainable.

My invention will be more readily understood by reference to the accompanying drawing illustrating the preferred form thereof and in which—

Figure 1 is a longitudinal section of a locomotive fire-box equipped with an arch embodying my invention; Fig. 2 is an enlarged transverse section substantially on the line 2—2 of Fig. 1; Figs. 3 and 4 are views similar to Fig. 2 but showing the arch in position in the furnaces of different widths and wherein the spaced relation of the arch tubes and the side sheets vary; Fig. 5 is a sectional view illustrating my arch arranged in a locomotive furnace equipped with four arch tubes; Fig. 6 is a perspective view of one of the unique bricks of my arch. Fig. 7 is a bottom plane view of the brick shown in Fig. 6; Fig. 8 is a detailed view 75 illustrating the modified form of arch brick; and Fig. 9 is a bottom plane view of the brick shown in Fig. 8.

The locomotives now in use as well as those which are continually being constructed vary in size, form, and arrangement with the result that the furnaces thereof also assume different shapes, sizes and proportions. Hence, in the practical designing of the locomotive furnace it is necessary, and desirable, 85 to space the arch tubes in some of the furnaces in a different manner than on others. For example, some of the wider furnaces require a greater number of arch tubes than the narrower furnace, and in some instances, 90 in furnaces of the same width, it is necessary to vary the spaced relation of the tubes and their relation to the side sheets. When equipping old locomotive furnaces with arch tubes, other conditions are also encountered 95 which prevent any regularity in the spaced relation of the arch tubes. It will thus be seen that in providing locomotive furnaces with arches, a great number of conditions must be met. I am aware that arches have 100 been devised for installation into furnaces of varying sizes and shapes and having different numbers of arch tubes. The practical arches hitherto devised, however, are composed of many differently shaped bricks 105 and many forms of bricks, *i. e.*, a single arch often requires a special arrangement or placing of these bricks within the arch itself.

Arches of such form are expensive to install and maintain. One reason for expensive maintenance lies in the fact that a manly form arch greatly increases the bricks 5 that must be carried in stock in the different repair shops.

I have devised a locomotive arch which is composed of but a single form of brick, which can be cheaply constructed and easily 10 installed, and any portion of which can be removed without disturbing or breaking down the remainder of the arch.

The advantages of my arch will be more readily understood by reference to the drawing 15 wherein 2 represents the flue sheet of a locomotive furnace, 3—3 the side sheets, 4 the rear sheet and 5 the crown sheet. The arch tubes 10 extend from the lower part of the 20 flue sheet 2 to the upper part of the rear sheet 4, thus occupying an inclined position well adapted for circulation of water from the front water leg 9 through the arch tubes and into the rear water leg 9''. As 25 stated, the number of tubes in an arch is dependent in a measure upon the size and type of the locomotive, as well as other factors in locomotive construction. While the arch here shown is a front arch, I wish it to be understood that my arch is adapted for use, 30 without material modification, as a rear arch.

Referring to Fig. 2 which is a cross-sectional view of the arch shown in Fig. 1, it will be seen that the tubes 10 are substantially 35 equally spaced one from the other and from the side sheets 3. This is the preferred arrangement since it is adapted best to bricks of uniform size, but other conditions often prevent such spacing. For convenience in description I shall refer to the two 40 tubes nearest respective side sheets as the side tubes. The tubes 10 serve to support a plurality of refractory bricks 12 which together serve to close the space between the 45 side sheets and form an arch or baffle wall. These brick, it will be noted, are identical in construction. Each brick has a grooved portion 13 for engagement with an arch tube 10. The brick is quite thick adjacent the 50 end containing the groove and tapers generally to a somewhat reduced end portion 14. At the thicker end of the tube I provide an inclined face 15 which extends up and rearwardly from the groove 13. The length and 55 the size of this brick may vary under certain conditions, but its length is usually slightly greater than the mean between all of the various spaced relations of the arch tubes with one another and of the spaced relation of the 60 side tubes and the side sheets that are met in practice. I find that bricks of such size are admirably adapted to construct arches under all the conditions named.

As is well shown in Fig. 2 certain of the 65 brick rest upon the side tubes of the group

and extend upwardly into engagement with the side sheet and others rest upon the arch tubes and extend into engagement with the inclined portion 15 of the brick next adjacent. It will be noted, therefore, that each 70 brick finds one of its supports directly upon the arch tube, and that the other end extends therefrom in lever-like manner and either abuts the side sheet or an inclined surface of the adjacent brick. In use these 75 bricks quickly wedge firmly into place.

In order that the danger of breaking the free end of the brick may be reduced, I prefer slightly to round it as indicated at 16. For the sake of convenience I shall term the 80 bricks which rest upon the arch tubes and extend in lever-like manner into engagement with the adjacent brick as the body of the arch, and the brick which extend between the side tubes and side sheets as side bricks. 85

In order that the support of the brick upon the arch tube may be increased and to the end that the likelihood of displacement therefrom may be reduced, I may provide lugs 17 which embrace a greater part of the 90 arch tube than the remainder of the brick and present a rigid arch. The bricks oppose each other and therefore prevent any displacement of the arch tubes. For some purposes it is not necessary to provide additional support upon the tubes in the form of lugs, in which case the brick may be made as shown in Figs. 8 and 9, with simply a groove extending across the lower end of the 95 brick.

To lighten the arch I prefer to recess it as indicated at 18. By reference to Fig. 3 it will be seen that the same brick is adapted for use in an arch in which the side sheets are much closer to the side tubes than in the 100 arch depicted in Fig. 2. Nor is special skill necessary in adapting my arch to the different furnaces as the bricks will of themselves find their proper position when once they are placed upon the tube.

In Fig. 4 I have illustrated the arch arranged in a locomotive furnace in which the distance between the side tubes and the side sheets is much greater than that between the respective tubes, but, as is evident by reference to that figure, the same bricks serve admirably for use in such a furnace.

In many of the arches hitherto devised, different forms of brick must be provided for every furnace having a different number of tubes. With my arch, however, a single brick form serves with any number of tubes which may be used. In Fig. 5 the arch is shown as applied to a four tube furnace.

Another result that should be carefully avoided when providing a locomotive furnace with an arch is that the fire does not play upon the side sheet higher at one side than at the other and that the distances be-

100

110

115

120

125

130

6 between the grate and the arch are not greater at one side than at the other. This result is avoided in my arch as both side sheets are exposed to the same extent and the spaces 10 40
6 between the grate and arch, cross-sectionally considered, are substantially the same throughout.

From this detailed description it is believed that the objects and advantages of 10 my novel arch will be apparent to those skilled in the art, but since modifications will readily suggest themselves, I do not desire to be limited to the exact construction 15 herein shown and described, except as may be necessary by express limitations in the claims hereunto appended.

I claim:

1. In a locomotive fire-box the combination of a group of arch tubes, the side tubes 20 being spaced from the side sheets, bricks resting upon the side tubes and abutting the side sheets, an inclined wedged portion on each brick adjacent the tube supported end, and other identical bricks having one 25 end supported on an arch tube and the other end resting upon and supported by the inclined wedge portions of the adjacent bricks.

2. In a locomotive furnace a group of 30 spaced arch tubes in combination with a plurality of bricks forming a refractory fire arch, each brick supported at one end only upon an arch tube, and extending therefrom in lever-like manner, and spanning the distance between adjacent tubes and having its 35 other end resting upon an adjacent brick.

3. In a locomotive furnace, the combination of a group of spaced arch tubes, with a plurality of identical bricks forming a

baffle wall in the furnace, each brick thereof resting at one end only upon an arch tube 40 and spanning the space between adjacent tubes, and an upstanding inclined brick-abutting portion on each brick at the tube supported end for co-operation with the end 45 of the adjacent brick.

4. In a locomotive furnace equipped with a group of longitudinally arranged and laterally spaced arch tubes, a plurality of identical refractory bricks forming an arch therein, each brick resting at one end upon 50 an arch tube and having an upstanding inclined portion at the tube supported end, the bricks supported upon the side tubes extending into wedging engagement with the side sheets of the furnace, and the other 55 bricks extending into wedging engagement with and being supported upon the inclined portion of the brick next adjacent.

5. In a locomotive furnace, a group of 60 arch tubes of less width than the fire-box, in combination with a brick arch arranged therein and composed of one brick form, each brick being supported at one end upon a tube and having a groove therein for complementary engagement with the tube, and 65 an inclined upstanding portion rising from the groove serving as a support for the end of the next adjacent brick.

In testimony whereof, I have hereunto set my hand, this 22nd day of September, 70 1913, in the presence of two subscribing witnesses.

ARTHUR W. NELSON.
